Primary Examiner — Kelley A Donnelly*(74) Attorney, Agent, or Firm* — Calfee, Halter & Griswold, LLP(57) **CLAIM**

I claim the ornamental design for a turntable, as shown and described.

DESCRIPTION

FIG. 1 is a front/left/top perspective view of a turntable; FIG. 2 is a rear/right/bottom perspective view thereof; FIG. 3 is a front elevational view thereof; FIG. 4 is a right side elevational view thereof (a left side elevational view would be a mirror image thereof); FIG. 5 is a front elevational view thereof; FIG. 6 is a top plan view thereof; and, FIG. 7 is a bottom plan view thereof. The broken lines depict portions that form no part of the claimed design.

1 Claim, 5 Drawing Sheets(56)
